HOSIERY KNITTING MACHINE

Anton Loimann, Chemnitz, Germany

Application February 8, 1934, Serial No. 710,333
In Germany February 22, 1933

3 Claims. (Cl. 66—98)

The invention relates to a presser capable of forward and retrograde movement for flat hosiery knitting frames. According to earlier proposals these presser devices were mounted under the sinker head, which has the very considerable disadvantage that the adjustable presser bar parts restrict the space for the knocking over combs. In order to eliminate the difficulties associated therewith it has even been suggested to mount comb shaped presser bar parts underneath the knocking over comb and to allow them to extend through the latter. In all these cases the presser bar was only accessible with difficulty and subsequent adjustment was inconvenient. In addition separate supporting devices for the presser bar were necessary.

According to another suggestion a presser bar comb was adapted to be suspended above the sinkers in the manner of a tickler machine, but this considerably affected the supervision of the machine. In addition a presser bar comb of this character must be withdrawn from the reach of the needles while placing the thread so that the knitting operation is retarded. It was further considered to retain the sinker bar underpart consisting of a number of relatively adjustable parts. In this connection however, the dividing points of the sinker bar underpart must each necessarily lie within the reach of a sinker so that no needle will be located within the reach of two presser bar parts projecting forwardly different distances and is exposed to the liability of being damaged. The sinkers provided at the said dividing points however cannot be guided reliably for this purpose. In the construction of knitting machines it has however, not been found possible to effect subdivision of the parts necessary for guiding the sinkers so that if possible they are omitted. It may also be mentioned that the width of the middle part of a subdivided sinker head underpart cannot be varied so that the use of these bar heads is restricted to a definite width of hosiery. An exchange of the sinker head underpart, however, is very inconvenient so that modifications and improvements are difficult to carry out.

An object of the present invention is to eliminate the defects of the known adjustable presser bars and particularly to avoid the necessity of providing separate bearing points for supporting the movable presser bar parts while still retaining easy supervision of the machine and a compact arrangement thereof. Another object of the invention is to facilitate the replacing of the presser bar parts used by others when chang-

ing to another method of operation for reasons of changing the pattern, without affecting the operation of the knitting machine.

According to the invention, the movable press parts are supported on the upper side of the sinker head and are so guided thereon that they overlap the latter and have their comb-like lower parts extend between the sinkers.

The accompanying drawings show an example of construction according to the invention:—

Figs. 1 and 2 show in vertical section and in plan respectively a simple form of construction of the invention of the application.

Figs. 3 and 4 show in vertical section and plan a form of construction which permits of a variation in width of the press part capable of retrograde movement.

Fig. 5 shows a sinker bar head with a modified construction of the adjustable presser bars, and the drive mechanism for the latter.

Fig. 6 shows in plan the attachment of the presser bars to an adjustable bar according to Fig. 5.

Fig. 7 is a cross-section through the adjustable bar with the clamped presser bars according to Fig. 5.

Fig. 8 shows a sinker bar head with an adjustable presser device extending over the whole front.

Fig. 9 shows the arrangement of a sinker bar head with an adjustable presser device and a knock-over comb arranged below the same, the knock-over bars arranged below the adjustable presser bars having shorter tongues than those which lie under the fixed presser bars.

In front of the two side parts of the needle bed the sinker head consisting of the upper part 1 and the under part 2 has the usual shape. Into the juxtaposed sides of the parts 1 and 2 is cut a large number of narrow slots for guiding the jack and dividing sinkers 3. The lower part 2 projects slightly beyond the front edge of the upper part 1 and forms the presser bar edge 10 which extends upwardly between the notched sinkers 3.

In order to enable a similar shaped retractable presser bar part to be provided in front of the middle part of the needle bed, a suitable recess 4 is provided in the front edge of the sinker head under part 2 and on the sinker head upper part 1 there is placed an auxiliary bar 5 which within reach of the middle bed part is provided with an inclined downwardly directed projection 6. This projection is formed at its lower edge into a press part 7 provided with pas-

sage slots for the sinkers 3 and which extends downwardly between these to such an extent that its front surface is adjustable in line with the lateral presser bar edges 10 of the sinker head 5 under part 2.

It is essential for the presser bar parts 7 for the middle part of the needle bed, and the presser bar parts for the side parts thereof to extend between the sinkers to effect a satisfactory 10 pressing.

When it is desired to so arrange the retractable press part 7 that its width is variable within predetermined limits whereby according to the type of stocking to be produced the foot portion 15 can be made narrower or wider, the downwardly extending projection 6' and the presser bar parts 7', according to Figs. 3 and 4, are made only of such a width as corresponds to the narrowest sole foot portion to be produced on 20 the machine in question. In this case, however, separate auxiliary presser bar parts 8 are adapted to be exchangeably secured to the bar 5 on both sides of the presser bar parts 7' so that according to the width of the foot portion required 25 at any time the retractable press parts can be made wider or narrower.

The auxiliary presser bar parts 8 are of similar shape to the above described retractable presser bar parts 7' except that their upper securing lug must be at such a level that it can be screwed firmly to the bar 5. The auxiliary presser bar parts 8 may be kept in stock in different widths and be so graded that the total widths 30 of the presser bar parts 7', 8, can be adapted to any suitable number of needles within the required limits. Each of the auxiliary presser bar parts 8 is provided with slots through which the sinkers 3 lying in the path thereof can pass. 35 If desired the auxiliary presser bar parts 8 may be clamped on the supporting bar 5 in the form of separate elements 8' as shown in Fig. 5. That part of the recess 4 of the sinker head under part 2 which is not filled by the auxiliary presser 40 bar part 8 is closed by additional parts 9 which are detachably secured for example bolted to one of the plate head parts 1 and 2 in any known manner. For this purpose there will also be kept in stock a set of additional parts of graded 45 widths so as to correspond to all requirements. 50

In Fig. 5, the presser bar 5 is shown slidable in the direction of the sinkers 3 on the top of the upper part 1 of the sinker head. The bar 5 carries the movable presser bar parts 8' (Fig. 7) 55 which are clamped between the part 1 and the clamping bar 11, the presser bar parts 8' being inserted in a corresponding groove machined on the upper side of the bar 5. These separate parts 8' are an alternative to the integral parts 60 5, 6, 7 of Fig. 1, and 7, 8 of Fig. 3.

At the two ends of the bar 5 are attached holder plates 12, 13 carrying pivot rods 14, 15 extending in the longitudinal direction of the bar 5. These pivot rods are engaged by levers 65 16, 17 pivoted intermediately on a fulcrum 18 carried by a bracket 19 fixed to the lower head member 2. The lower ends of the levers 16, 17 are jointed by pins 21 to the ends of drive links, not shown. In connection with lever 17 of Fig.

9 any suitable cam and intermediate members may be employed to operate said lever.

The retractable middle presser bar parts enable the middle part of the needle bed to be excluded from the stitch forming operation without it being necessary for this purpose to subdivide the needle bar. This fact is of particular importance when, for example, the middle part of stockings is to be excluded from the stitch forming operation during the formation of the heel flaps and to be brought in the known manner under the knocking-over comb for preserving the stitches last formed, while the knocking-over comb at the corresponding points is to be made shorter than at the other points. When this method is carried out according to the known proposals, the heel angle has a shape differing somewhat from the normal as it has to be provided with a longer slot than is necessary for the production of the heel flaps. This can be avoided when the needle bar is of undivided construction and the middle press part is arranged to be retractable. It is, therefore, of particular importance when the knocking-over notched combs within reach of the retractable presser bar parts are made shorter 25 than the non-adjustable press parts. This is shown in Fig. 9. The reference character 10 in Figs. 1, 8, and 9 indicates an auxiliary bar which serves the purpose of securing the elements 8' to the bar 5.

It is also possible as shown in Fig. 8 to arrange the presser bar for retrograde movement over its entire width and to arrange its drive in such manner that it is always advanced into the operative position directly before the press 35 operation and thus renders unnecessary the rocking movement of the needle bar which is now usual. In this connection it is of particular advantage that the sinker head need not partake of the movements of the presser bar.

I claim:—

1. In a machine for knitting flat hosiery, a sinker bar head, and a movable presser bar guided on the upper side of the sinker bar head and extending from the upper side thereof downwardly in front of said head.

2. In a machine for knitting flat hosiery, a sinker bar head having upper and lower members, a retractable presser bar guided on the upper member of the sinker bar head, presser bar parts integral with said bar and extending downwardly into a recess in the lower member of the head, exchangeable auxiliary presser parts at both sides of the integral presser bar parts and also extending into the recess, and stationary presser bar parts fixed to the sinker bar head and filling portions of said recess not occupied by the retractable presser bar parts.

3. In a machine for knitting flat hosiery, a sinker bar head, a presser bar having retractable parts guided on the upper side of the sinker bar head and extending from said upper side downwardly in front of the head and also fixed parts, and knocking over combs arranged in the range of action of said retractable and fixed presser bar parts, the combs located below the retractable parts being shorter than the combs below the fixed parts.

ANTON LOIMANN.
